UNITED STATES PATENT OFFICE.

HARRY SWINGLEHURST, OF PHILADELPHIA, PENNSYLVANIA, ASSIGNOR, BY MESNE ASSIGNMENTS, TO SCOTT & WILLIAMS, INCORPORATED, OF CAMDEN, NEW JERSEY, A CORPORATION OF NEW JERSEY.

KNITTING-MACHINE.

1,035,656.

Specification of Letters Patent. Patented Aug. 13, 1912.

Application filed February 25, 1907. Serial No. 359,096.

To all whom it may concern:

Be it known that I, HARRY SWINGLEHURST, a citizen of the United States, residing in Philadelphia, Pennsylvania, have invented 5 certain Improvements in Knitting-Machines, of which the following is a specification.

My invention relates to knitting machines in which a set of latch needles is mounted 10 at an angle to another set of co-acting devices, such for instance, as the other needles in an ordinary rib knitting machine; transfer points, in a machine for knitting open work fabrics; web holders, in a plain web 15 machine; or loopers in a machine for knitting fabric with fleecing yarn combined therewith, the object of my invention being to so construct such a machine as to prevent the latches of the needles from coming into 20 contact with the devices with which said needles co-act in the operation of the machine, and thereby producing defective work or causing injury to the latches or other parts of the machine. This object I at- 25 tain in the manner hereinafter set forth, reference being had to the accompanying drawing, in which:—

Figure 1 is an exaggerated plan view of part of the needle cylinder, needle dial, cylinder cam ring, and dial cam cap of an ordinary circular rib knitting machine, illustrating the defect in the latter which my invention has been designed to overcome, and Figs. 2, 3 and 4 are views illustrating means 35 in accordance with my invention for remedying this defect.

In rib knitting machines of fine gage in which the cylinder and dial needles operate in close proximity to one another difficulty 40 has been experienced because of contact of the latches of the cylinder needles with adjoining dial needles in the opening or closing movement of said latches, this defect being due partly to the twisting of the needle 45 in the needle groove of the cylinder under the thrust of the cams upon its projecting butt, and partly to looseness of fit between the latch and the needle shank, the defect being exaggerated as the parts wear and 50 consequently are susceptible of more and more motion. The nature of the defect will be understood on reference to Fig. 1 of the drawing, in which 1 represents the needle cylinder of the machine, 2 the cylinder cam

ring which has movement in respect to the 55 needle cylinder, as indicated by the arrow, 3 the cylinder needles, 4 their latches, 5 the dial needles, 6 the needle dial, and 7 the dial cam cap.

The normal plane of movement of the 60 cylinder needle latch 4 would be that of the radial line x , but owing to the causes before mentioned, the actual plane of movement of said latch is so distorted that in machines of fine gage, it has a tendency to come into 65 contact with the adjoining dial needle 5, as shown.

One means which I have devised to overcome the defect is to slightly incline the needle-guiding grooves of the cylinder in respect to a radial line drawn from the axis of the cylinder, or so that they will not be perpendicular to the face of the cylinder, as shown in Fig. 2, the inclination of the grooves being forwardly or in a direction 70 the reverse of the direction of movement of the cylinder cam ring in respect to the cylinder, or, in case the cylinder is the moving member, in the direction of such movement. In the claims I have used the term "acute 75 angle" in order to indicate this disposition of the grooves. By this means those factors which before operated to deflect the latch from its normal working plane, now operate to cause it to assume that plane, as shown in 80 Fig. 2, consequently the latch moves in its intended relation to the following dial needle, and interference of one with the other is prevented. The same result may be at- 85 tained by so disposing the grooves which re- 90 ceive the dial needles that said grooves are not perpendicular to the edge of the dial, but are so inclined as to be parallel with the abnormal planes of movement of the cylinder needle latches, as shown in Fig. 3. In 95 some cases, it may be advisable to adopt this construction in the dial as well as in the cylinder, that is to say, the dial needle grooves will not be perpendicular to the face of the dial. Such construction is shown in Fig. 4, 100 and the dial may have the grooves thus inclined, and also inclined in the manner shown in Fig. 3.

I make no claim herein to the dial having its guide grooves so disposed as to bisect radial lines drawn from the center to the periphery of the dial or to a knitting machine containing such a dial as that invention

forms the subject of a divisional application filed by me on the 11th day of April, 1912, Serial No. 690,146.

Although I have shown my invention as applied to a circular machine, it is equally applicable to straight bar machines, and the terms "cylinder" and "dial" as used in the claims are intended to cover segments of such members, as well.

10. As before indicated, my invention is not limited to machines in which both members carry latch needles, as but one of said members may be thus equipped, the other member carrying transfer points, web holders, 15 fleecing yarn loopers, or the like, whose planes of operation are such as would cause them to be fouled by the latches of the needles in the absence of the preventive measures which I have devised.

20. I claim:

1. A knitting machine member having therein grooves which guide in their reciprocating movements knitting instrumentalities placed therein but which are disposed at 25 an acute angle to the face of said member, as and for the purpose set forth.

2. A knitting machine needle carrier having therein grooves which guide the needles in their reciprocating movement, but which 30 are disposed at an acute angle to the face of the needle carrier, as and for the purpose set forth.

3. A knitting machine cylinder having 35 therein needle-guiding grooves which are at an acute angle to the face of the cylinder, as and for the purpose set forth.

4. A knitting machine having two members disposed at an angle to each other, and coöperating knitting instrumentalities 40 guided in grooves in said members, those of

one member working in the spaces between those of the other member, and one member having grooves which are at an acute angle to the face of the said member whereby to prevent the implements guided by said grooves from crossing the planes of movement of the implements guided in the grooves of the other member.

5. A knitting machine needle carrier having needle-guiding grooves inclined in respect to the normal plane of movement of the needle latch, as and for the purpose set forth.

6. A knitting machine having two members disposed at an angle to each other, 55 coöperating knitting instrumentalities guided in grooves in said members, one member having grooves which are disposed at an acute angle in respect to the face of the same, whereby parallelism is established 60 between the instrumentalities mounted in said grooves and those mounted in the grooves of the other member.

7. A knitting machine having two members disposed at an angle to each other, 65 coöperating knitting instrumentalities guided in grooves in said members, one member having grooves which are disposed at an acute angle to the face of the same, whereby parallelism is established between 70 the implements guided in said grooves and those guided in the grooves of the other member.

In testimony whereof, I have signed my name to this specification, in the presence of 75 two subscribing witnesses.

HARRY SWINGLEHURST.
